(57) **CLAIM**

The ornamental design for a bag holding tray, as shown and described.

DESCRIPTION

FIG. 1 is a top-front-left perspective view of a bag holding tray showing my new design;
FIG. 2 is an enlarged view of area 2 encircled in FIG. 1;
FIG. 3 is an enlarged view of area 3 encircled in FIG. 1;
FIG. 4 is a top-front-right perspective view of the bag holding tray;
FIG. 5 is an enlarged view of area 5 encircled in FIG. 4;
FIG. 6 is an enlarged view of area 6 encircled in FIG. 4;
FIG. 7 is a bottom-rear-left perspective view of the bag holding tray;
FIG. 8 is an enlarged view of area 8 encircled in FIG. 7;
FIG. 9 is a bottom-rear-right perspective view of the bag holding tray;
FIG. 10 is an enlarged view of area 10 encircled in FIG. 9;
FIG. 11 is an enlarged view of area 11 encircled in FIG. 9;
FIG. 12 is a top view of the bag holding tray;
FIG. 13 is an enlarged view of area 13 encircled in FIG. 12;
FIG. 14 is an enlarged view of area 14 encircled in FIG. 12;
FIG. 15 is a bottom view of the bag holding tray;
FIG. 16 is an enlarged view of area 16 encircled in FIG. 15;
FIG. 17 is an enlarged view of area 17 encircled in FIG. 15;
FIG. 18 is a front view of the bag holding tray;
FIG. 19 is an enlarged view of area 19 encircled in FIG. 18;
FIG. 20 is a rear view of the bag holding tray;
FIG. 21 is an enlarged view of area 21 encircled in FIG. 20;
FIG. 22 is a left side view of the bag holding tray; and,
FIG. 23 is an enlarged view of area 23 encircled in FIG. 22.
The broken lines in the drawings depict portions of the bag holding tray that form no part of the claimed design.
The dot-dot-dash broken lines depict the boundaries of the claim and form no part thereof.
